SAWHORSE

Robert A. Gilmour, ½ Gilmour Manufacturing Co.,
Somerset, Pa.

Filed Apr. 9, 1963, Ser. No. 74,366

Term of patent 14 years

(Cl. D54—1)

FIGURE 1 is a perspective view of one form of a sawhorse embodying the invention;

FIGURE 2 is a rear elevation of one of the supporting legs shown in FIGURE 1 with portions omitted for convenience of illustration;

FIGURE 3 is a side elevation thereof as shown in FIGURE 2;

FIGURE 4 is a modified form of the sawhorse shown in FIGURE 1;

FIGURE 5 is a rear elevation of one of the supporting legs shown in FIGURE 4 with portions omitted for convenience of illustration; and

FIGURE 6 is a top plan view thereof as shown in FIGURE 4.

The dominant features of the invention are shown in solid lines.

I claim:

The ornamental design for a sawhorse, as shown and described.
